AMPLIFYING ARRANGEMENT COMPRISING
THERMIIONIC TUBES HAVING MORE THAN
ONE GRID

Klaas Posthumus, Eindhoven, Netherlands, assignor to Radio Corporation of America, a corporation of Delaware

Application April 19, 1934, Serial No. 721,295
In Germany April 7, 1933

2 Claims. (Cl. 179—171)

This invention relates to circuit arrangements for amplifying high frequency oscillations in which thermionic tubes are used having more than one grid, for instance, screening grid tubes.

As is well known a reaction of the anode circuit on the controlling grid circuit and of the other grid circuits on the controlling grid circuit can occur with thermionic tubes having more than one grid. This reaction is due to the capacities of the various electrodes of the thermionic tubes with respect to each other. It manifests itself the more as the frequency of the high frequency oscillations to be amplified is higher and it may eventually acquire such a value that the arrangement begins to self-oscillate. If the anode-controlling grid capacity is made very small as is the case for instance, with screening grid tubes, the reaction of the anode circuit on the controlling grid circuit caused by this capacity will be small so that it may be neglected. In spite thereof a certain reaction of the anode on the controlling grid circuit will still occur also with screening grid tubes, if the frequency of the alternating currents to be amplified is very high, viz. through the anode-screening grid capacity and the screening grid-controlling grid capacity. This would be impossible, it is true, if the screening grid were short-circuited for high frequency oscillations with the cathode. However, the connecting wires required for connecting the screening grid to the cathode, which wires are partly provided within and partly outside the envelope of the tube, have a certain self-induction, so that a high frequency alternating tension will be set up between the screening grid and the cathode, which tension acts more and more through the screening grid-controlling grid capacity on the controlling grid circuit as the frequency is made higher and the impedance in the anode circuit becomes larger.

Besides being coupled through the screening grid-controlling grid capacity, the screening and the controlling grid circuits are coupled together through the mutual self-induction of the screening grid and of the controlling grid, by which a reaction of the first mentioned circuit on the last mentioned circuit is also caused.

Both electrostatic and inductive couplings of other electrodes with the controlling grid are present not only in screening grid tubes but also in other tubes having a plurality of grids. The invention has for its purpose to provide means by which the reaction in tubes having a plurality of grids in consequence of the said causes is avoided.

According to the invention this is achieved by establishing a high frequency connection between the end of the impedance in the anode circuit remote from the anode and a grid which is not used as a controlling grid, in such a manner that the part of this connection which is common to the circuit connecting the said grid to the cathode, has a small impedance for high frequency currents.

The invention will be more clearly understood by reference to the accompanying drawing, representing by way of example, two embodiments thereof. In the drawing:

Figure 1 shows a circuit arrangement for amplifying high frequency oscillations in which a screening grid tube is used; and,

Figures 2 and 3 are schematic amplifier circuit arrangements showing different embodiments of my invention.

The screening grid tube comprises an anode A, a screening grid S, a controlling grid G and a cathode K. The latter may be heated either directly or indirectly. For the sake of clearness all sources of direct tension or potential have been left out in Fig. 1, since only high frequency currents are considered. The anode circuit of the screening grid tube comprises an impedance Z_a constituted, for instance, by a resonant circuit consisting of an inductance L_a and a condenser C_a . The controlling grid circuit comprises an impedance Z_g consisting, for instance, of an inductance L_g and a condenser C_g . Furthermore, the anode-screening grid capacity is denoted in the drawing by C_{as} and the screening grid-controlling grid capacity by C_{sg} . The wire connecting the screening grid to the cathode which may be provided partly within and partly outside the envelope of the tube, has a definite self-induction L_s depending on the wire length. This self-induction is connected in series with the anode-screening grid capacity C_{as} to form a path in parallel with the impedance Z_a inserted in the anode circuit.

In the case represented in Figure 1 in which Z_a consists of a resonant circuit, the current traversing the capacity C_{as} and the inductance L_s can become large and even greatly exceed in strength the anode current passing through the tube. This results from the fact that the capacity C_{as} forms a part of the oscillatory circuit and at high frequencies the current passing through C_{as} and L_s will usually be many times greater than the total current passing through the tube anode. If the frequency of the alternating currents to be amplified is high

and the connecting wire is long, as for instance is the case with screening grid transmitting tubes, the voltage drop caused by the current through the inductance L_s of the connecting wire, will also become large. The consequence of this fluctuating voltage set up between the screening grid and the cathode is a reaction of the screening grid through the screening grid-controlling grid capacity C_{sg} on the controlling grid circuit. With an increasing frequency of the alternating currents to be amplified this reaction manifests itself more and more, so that the amplifying arrangement has eventually a tendency to self-oscillate.

According to the invention this risk is avoided with the arrangement shown in Fig. 2, in which the end of the impedance Z_a in the anode circuit remote from the anode is not immediately connected for high frequency oscillations to the cathode K but to a terminal P . This terminal which may lie outside the envelope of the tube is so arranged that only a very short connection is required between it and the screening grid. It will be appreciated that in the arrangement represented in Figure 2 alternating currents traversing the connecting wire 10 from the terminal P , consequently from the screening grid, to the cathode K are much smaller, since this connecting wire no longer forms part of the resonance circuit Z_a , which was the case in the arrangement represented in Figure 1. The traversing current will correspond to the sum of the anode alternating current and the screening grid alternating current. If the resonant circuit Z_a is tuned to the frequency of the alternating currents to be amplified, then the anode current will be in phase with the alternating current or voltage impressed on the controlling grid. This also holds good for the screening grid alternating current. So that the alternating current component passing through lead 10 is many times smaller than the circulating current of the resonance circuit and therefore the potential of point P will not fluctuate greatly with reference to the cathode and, as the lead a is made as short as feasible, the potential of the screen grid will fluctuate only a small amount and hence cause only slight reaction on the control grid. The small voltage drop through wire 10 is in part due to the very low self-inductance of this lead.

Hitherto the coupling occurring between control and screening grids due to their mutual self-induction was disregarded. However, this coupling also will manifest itself at a sufficiently high frequency of the alternating currents to be amplified by the tube and increase with amplifying arrangements the tendency to self oscillate.

By using the arrangement represented in Fig. 3 this reaction also can be rendered substantially ineffective in addition to the reaction caused by the capacity between screen grid and control grid. In this figure the screening grid S is connected not only to a terminal P through a short con-

necting wire a , but also to a terminal Q through a connecting wire b . The terminal Q is maintained at the same radio frequency potential as the low potential end of circuit Z_a by the direct connection shown. The connecting wire b is connected to a point R of the screening grid, so that the currents traversing the anode-screening grid capacity set up an opposite magnetic field in the parts of the screening grid on the left and on the right of the point R , by which field the inductive effect of the screening grid on the controlling grid is substantially neutralized.

By arranging the point R not exactly in the middle of the screening grid, but by spacing it apart therefrom, the average voltage of the screening grid can be kept constant with respect to the controlling grid, owing to which also the electrostatic reaction through the capacity C_{sg} decreases. In the circuit shown in Fig. 3, as in that of Fig. 2, the large circulatory currents of the resonant circuit do not flow through the lead 10 connecting the cathode and terminal P and thereby cause substantial voltage variations of the screen grid. On the contrary the screen grid potential remains substantially the same as that of the cathode so that the reaction caused by the screen grid on the control grid due to the capacity therebetween is minimized.

Although in the description and in the drawing the use of the invention is suggested for screening grid tubes, it will be appreciated that it may also be used to advantage in other tubes having a plurality of grids, for instance pentodes.

Having described my invention, what I claim as novel and desire to secure by Letters Patent is:

1. In an amplifier arrangement, the combination of a vacuum tube having a cathode, a control grid and a plate, a second grid located between the control grid and plate, an input circuit connected to said control grid and cathode, a terminal located adjacent said second grid, a short lead connected between said terminal and said second grid, a connection from said terminal to the cathode, said connection having such impedance which together with the anode-screen grid capacity form a path of negligible impedance to high frequency currents, and an output circuit having its low potential end directly connected to said terminal.

2. An amplifying device comprising the combination of a vacuum tube having a cathode, an anode, a control grid and a screen grid located between said control grid and anode, a resonant input circuit connected across said cathode and control grid, a second circuit resonant to substantially the same frequency as said input circuit having its high potential end connected to said anode, a conductor directly connected between the screen grid and cathode, and a connection from the low potential end of the second resonant circuit to a point on said screen grid conductor close to the screen grid.
